DESCRIPTION

FIG. 1 is a perspective view of a tap base in accordance with aspects of the present subject matter.

FIG. 2 is a side view of the embodiment of the tap base illustrated in FIG. 1, with the opposing side being a mirror image thereof.

FIG. 3 is a top view of the embodiment of the tap base illustrated in FIG. 1.

FIG. 4 is a bottom view of the embodiment of the tap base illustrated in FIG. 1.

FIG. 5 is a front view of the embodiment of the tap base illustrated in FIG. 1; and,

FIG. 6 is a top, exploded view of the embodiment of the tap base illustrated in FIG. 1.

Any broken lines contained within the figures, including, but, not limited to, any dash-dot broken lines and/or dash-dot-dot broken lines, represent portions of the tap base that form no part of the claimed design. Additionally, contour lines and/or surface shading, to the extent applicable, are illustrated simply for purposes of highlighting the solid-rendering, and, thus, form no part of the claimed design. The present design is not limited to the exact details shown in the drawings, since equivalents and colorable imitations thereof will be evident to a person of ordinary skill in the art. Within the scope of the appended claim, in which we intend to cover only the ornamental and novel elements shown in the drawings, the present design may be practiced otherwise than as specifically shown and described herein.

Any combination of the illustrated features, including claimed features and unclaimed features, may be claimed in this application or a continuing application claiming priority to this application by converting any portion of the broken lines to solid lines, any portion of the solid lines to broken lines, or both.
